UNITED STATES PATENT OFFICE.

JESSE A. HOWLAND, OF SEA BRIGHT, AND WILLIAM H. DE NYSE, OF LONG BRANCH,
NEW JERSEY.

SEA-GROIN.

No. 897,369.

Specification of Letters Patent.

Patented Sept. 1, 1908.

Application filed December 10, 1906. Serial No. 347,061.

To all whom it may concern:

Be it known that we, JESSE A. HOWLAND, a resident of Sea Bright, in the county of Monmouth and State of New Jersey, and 5 WILLIAM H. DE NYSE, a resident of Long Branch, in the county of Monmouth and State of New Jersey, both citizens of the United States, have invented a new and Improved Sea-Groin, of which the following is 10 a full, clear, and exact description.

The invention relates to hydraulic engineering, and its object is to provide a new and improved sea groin or like structure designed for use along the coast in harbors, rivers and other water ways, and arranged to form a permanent structure capable of withstanding the ravages of the waves, teredos and other destructive causes.

The invention consists of novel features 20 and parts and combinations of the same, which will be more fully described herein-after and then pointed out in the claims.

A practical embodiment of the invention is represented in the accompanying drawings 25 forming a part of this specification, in which similar characters of reference indicate corresponding parts in all the views.

Figure 1 is a plan view of the improvement; Fig. 2 is a face view of the same, parts 30 being broken out; Fig. 3 is a transverse section of the same; Fig. 4 is an enlarged sectional plan view of two interlocked reinforced concrete planks; Fig. 5 is a cross section of a modified form of the improvement with false 35 work for supporting the concrete planks; Fig. 6 is a face view of the same, parts being broken out, and Fig. 7 is an enlarged sectional plan view of two interlocked concrete planks.

40 The structure illustrated in Figs. 1, 2 and 3 consists of a wooden support A for the planks B, made of reinforced concrete so as to be permanent and not liable to the destructive work of teredos and the like. The 45 support A consists of piles A' driven into the bottom of the sea, river or other water way to the desired depth, and on the said piles A' are secured by bolts C two or more rows of 50 concrete planks are fastened by the use of bolts C', C''. The upper ends of the planks B are protected by an outer stringer D fastened in place by the bolts C' previously mentioned, so as to stiffen and protect the upper 55 ends of the concrete planks B as much as

possible. By the arrangement above described the structure A is rendered permanent and the planks B are of a length sufficient to extend a distance down into the bed of the sea, river or other water way, so as to 60 form a protection against the destructive action of the waves, at the same time the planks are not liable to be destroyed by the action of teredos.

In making a plank of concrete, one side is 65 provided with a tongue B' and the other side with a groove B'', so that the tongue of one plank readily fits into the groove of the adjacent plank to properly interlock the planks with each other. The body of concrete for 70 each plank is reinforced in the direction of its length by metallic rods B³, and the tongues B' are reinforced by metallic strips or plates B⁴, and similar plates B⁵ are used for reinforcing the side walls of the grooves B'', so as 75 to render the tongues and grooves exceedingly strong and durable.

In the structure illustrated in Figs. 5, 6 and 7 the support E is in the form of false work, and although it first supports the reinforced 80 concrete planks F it is liable to destruction without, however, seriously impairing the usefulness of the interlocked concrete planks F. For this purpose the planks F are of a length approximately corresponding to the 85 piles E', so that the planks F are driven a considerable distance down into the bottom of the sea, river or other water way, to render the planks self-sustaining, and consequently the planks remain in position even after the 90 wooden structure E has rotted away or is otherwise destroyed. As shown, the stringers E², E³ are secured to the piles E' by bolts G, and the planks F are secured to the stringers by bolts G'. The upper ends of the planks 95 F are formed with heads F' resting on the top of the uppermost stringer E², and the corners of the interlocked planks are stiffened and protected by metallic caps H and H', preferably in the form of angle-irons, fastened by 100 bolts or rivets H' to the heads F' of the planks. Thus by the arrangement described, the upper ends of the interlocked concrete planks are strongly stiffened and protected, to prevent the same from chipping off.

In using the self-sustaining planks as above described, it is preferred to provide one side of a plank with a dovetail tongue F² and the other side with a correspondingly-shaped dovetail groove F³, as will be readily under- 110

stood by reference to Fig. 7. The plank F is reinforced in the direction of its length by metallic rods F⁴, and the tongue F² is reinforced by a metallic plate F⁵, and the walls of the groove F³ are reinforced by similar plates F⁶, so as to render the interlocked planks F exceedingly strong and durable.

From the foregoing it will be seen that a structure as shown and described is rendered permanent by the use of interlocked reinforced concrete planks, not liable to the destructive action of waves, teredos and like causes.

In building the structure the spaced piles are driven down into the bed of the sea or water way, and then the stringers are attached to the piles to form the wooden support for the concrete planks. The latter are then driven down into the bed of the sea or water way along the stringers as guideways and are fastened to the stringers as described, and the planks are interlocked with each other by their tongues and grooves, thus forming a sheet planking of driven concrete planks, which are supported partly by the bed of the water way and partly by the wooden support, thus forming an exceedingly strong planking capable of withstanding the action of the sea and the destructive work of the teredos.

Having thus described our invention we claim as new and desire to secure by Letters Patent:

1. A sea groin or like structure comprising a false work of piles and stringers, and interlocked reinforced concrete planks, said planks being arranged vertically and secured to the said stringers with their lower ends extending into the bed of the water way.
2. A sea groin or like structure comprising a false work of piles and stringers, and interlocked reinforced concrete planks of self-sustaining length and secured to the said stringers, the upper ends of the planks pro-

jecting upward beyond the top of the false work.

3. A sea groin or like structure comprising a false work of piles and stringers, interlocked reinforced concrete planks of self-sustaining length and secured to the said stringers, the upper ends of the planks projecting upward beyond the top of the false work, and metallic protectors for the upper ends of the said planks.

4. A sea groin or like structure comprising a false work of piles and stringers, interlocked reinforced concrete planks of self-sustaining length and secured to the said stringers, the upper ends of the planks terminating in a head resting on the upper stringer, and metallic caps for the corners of the said heads.

5. As a new article of manufacture a plank for sea groins and other hydraulic structures and consisting of a body of concrete in the form of a plank, and metal bars extending lengthwise in the said body for reinforcing the plank, one side of the body having a reinforced tongue and the other side being provided with a reinforced groove.

6. As a new article of manufacture a plank for sea groins and other hydraulic structures, consisting of a body of concrete in the form of a plank and having a tongue at one edge and a groove at the other, metal bars extending lengthwise of the body of the plank for reinforcing the same, a metal plate extending lengthwise of the tongue, and a metal plate extending lengthwise in each wall of the groove.

In testimony whereof we have signed our names to this specification in the presence of two subscribing witnesses.

JESSE A. HOWLAND.
WILLIAM H. DE NYSE.
